UNITED STATES PATENT OFFICE.

ARTHUR ATWATER KENT, OF PHILADELPHIA, PENNSYLVANIA.

DEVICE FOR UNITING INSULATED CONDUCTORS OF ELECTRICITY.

1,082,811.

Specification of Letters Patent.

Patented Dec. 30, 1913.

Application filed January 24, 1911. Serial No. 604,432.

To all whom it may concern:

Be it known that I, ARTHUR ATWATER KENT, a citizen of the United States, and a resident of the city of Philadelphia, county of Philadelphia, and State of Pennsylvania, have invented certain new and useful Improvements in Devices for Uniting Insulated Conductors of Electricity, of which the following is a full, complete, and exact disclosure.

My invention relates to devices for attaching an insulated wire to another conductor, and my invention particularly relates to the attaching of such an insulated wire as is used for currents of high potential to a stationary conductor, terminal or contact, of any suitable electrical apparatus.

Considerable difficulty has always attended the attaching of an insulated electrical conductor adapted to be used in connection with high tension currents to a contact terminal, or other insulated conductor, particularly where the wire should be rigid and immovable with respect to such terminal or the support in which the same is mounted. An instance of such a use as is contemplated by my invention is in attaching a secondary circuit wire of an inductive circuit of a sparking system for internal combustion engines. In such and similar circuits it is particularly desirable that the wire be coupled or united to the terminal rigidly and at the same time completely insulated from everything but the terminal. Further than this, in order to prevent any leakage in the circuit in the connection, or coupling, the interior of the same should be watertight, for if water could find its way into the connection there would be great liability of an electrical leak or a short circuiting or grounding of the circuit, and it is a further object of my invention to provide a coupling to fulfil all the conditions or requirements above referred to in a simple, inexpensive and convenient manner.

In the drawings forming a part of this application in which the same reference numerals are used to designate the same parts throughout the various views, Figure 1 is a plan view of a support or other suitable mounting provided with my improved means for uniting wires to a terminal provided therein; Fig. 2 is a vertical sectional view on the line 2-2 of Fig. 1, and Figs. 3, 4 and 5 are vertical sectional elevations of modified forms of my invention.

Referring first particularly to Figs. 1 and 2, a support 1, which may be a casing or other part of any suitable piece of electrical apparatus, is provided with a contact piece or stationary conductor 2, to which an ordinary relatively flexibly insulated conductor 8 is to be electrically connected. The support 1 around and adjacent the conductor 2 is preferably provided with a cylindrical projection 1' upon the outer surface of which are screw threads 3. The contact or stationary conductor 2 is embedded or otherwise suitably secured to the support 1, and the end thereof which is to be attached to the insulated wire may be and preferably is provided with a recess or hole 4, the diameter of which is slightly larger than that of the bare wire of the insulated conductor to be attached thereto. The projection 1' is provided with a smooth bore or cylindrical hole 5, the bottom of which adjacent and surrounding the conductor or contact 2, is preferably conical or flaring away from the end of said terminal 2. Over the threaded surface of the support is an internally threaded cap or coupling 6, which is provided on its outer end with an opening 7 for the passage of the insulated conductor 8 therethrough. The inside of said cap or coupling 6 is preferably provided with a shoulder 9, the purpose of which will be made plain below. In attaching the conductor 8 to the contact or conductor 2, I first pass the conductor through the opening 7 of the cap or coupling 6, and remove the insulation from the end 8' of the conductor so that the end 8' will come into electrical contact with the conductor 2, the said end, in the forms of my device as shown in Figs. 2 to 4 entering the recess or hole 4 in the contact or terminal 2. I then wrap around the end of the conductor 8, preferably over the insulated surface thereof, and adjacent the bared end 8', a number of convolutions of adhesive tape 10 until the outer diameter of the wound tape is substantially the same as the diameter of the bore 5 in the projection 1'. The bared end 8' of the conductor 8 is then brought into engagement with the conductor 2 by inserting the same into the hole 4 of the contact or conductor 2, and the convolutions 10 of the tape will form a collar or flange which will substantially fill the bore 5. The cap or coupling 6 is then drawn over the conductor 8 and threaded or screwed over the exterior surface of the pro-

junction 1' surrounding the contact or conductor 2. In doing this the shoulder 9 of the cap or coupling 6 engages the outer side or edges of the convolutions of the tape 10 and forces the same down against the conical surface 5' of the bore 5, and in so doing forces the bared end of the conductor 8 into electrical engagement with the conductor 2 and compresses or expands the tape 10 radially so that it will snugly fit and fill the bore 5 of the projection 1', but having first filled the said opening or bore its radial expansion is limited by the walls of the projection 1' surrounding the said bore 5.

15 It is well known that when a flexible material such as adhesive tape is spirally wrapped around a surface it binds very tightly on the surface upon which it is thus wrapped and there is a great deal of pressure exerted by the convolution material upon the said surface, this principle being illustrated when a cord is wrapped in a number of convolutions around the finger. It will be seen then that when the adhesive tape is so wound or wrapped around the conductor 8 it holds or grips the same very tightly and under considerable pressure due to the winding or wrapping of the same around the conductor. In addition to the tension which is put upon the insulated conductor by reason of these convolutions of tape 10 the same is further compressed against the sides of the conductor by the conical surface 5' when the cap 6 is screwed over the threaded surface 3. The shoulder 9, engaging the outer side or edges of the convolutions of tape 10 around the opening 7, may be pushed against it sufficiently tightly to make a watertight joint at this point. The insulated wire or conductor 8 so attached to the terminal is held substantially immovable with respect thereto, for it is slightly expanded by the pressure exerted upon it by the coupling and fills the opening 5 in the projection 1', and it is clamped between the shoulder 9 and the conical surface 5', which conical surface has a crowding or wedging action on the adjacent ends or wedges of the tape 10. By reason of this the wire is so firmly held and clamped that it cannot be twisted or turned within the coupling, and the bared end 8' is firmly held in position in the recess 4 of the terminal forming a sufficiently good electrical connection for a high tension current between the end of the conductor and the terminal.

60 By means of this invention it will be observed that no separate clamps or set screws or other holding devices are necessary, and that to unite the wire or conductor to the contact or other conductor it is merely necessary to wrap the end with a number of convolutions of adhesive tape so that it will fit fairly snugly within the opening adjacent

the end of the conductor 2 and screw the coupling down on to the support or mounting.

In Fig. 3 I have illustrated the same construction except that instead of adhesive or sticky tape, a flexible twine or cord 11 is employed, the same being wrapped around the end of the conductor in a plurality of convolutions in a manner similar to that in which the tape is wound in the embodiment of my invention illustrated in Figs. 1 and 2. The same principle of the tight grip of a flexible material wrapped around a surface in a number of convolutions, is made use of in this construction, and I find that the wire or flexible conductor 8 is very rigidly secured and held in this manner.

In Fig. 4 a single rubber ring or washer 12 is employed in lieu of the adhesive tape 10 or twine or cord 11, and when the cap or coupling 6 is threaded down over the threaded surface of the support, the rubber washer 12 will be expanded to completely fill the interior of the bore in the projection of the support, and at the same time forced inwardly and firmly against the conductor to grip the same and hold it immovable with respect to the terminal, but when the washer 12 fills the opening 5 its further radial expansion will be limited by the walls of the said opening.

Instead of one washer 12, as is shown in Fig. 4, a plurality of rings or washers 13 may be used as in the construction illustrated in Fig. 5, and the same will be compressed to substantially fill the opening adjacent the conductor 2, and grip the conductor 8 as has been above described.

In some cases it may not be necessary to provide the end of the conductor 2 with a recess 4 for the bared end of the wire is held so firmly by the tape, twine or cord or elastic washers that it cannot be moved laterally or separated from its engagement with the conductor 2 after the cap 6 has been screwed down in place and the washers or other gripping means have been compressed to fill the opening or bore around and adjacent the end of the terminal 2. This I have illustrated in Fig. 5, it being understood that in any of the modifications previously described the hole 4 in the end of the conductor 2 may be dispensed with if so desired.

The forms of my invention illustrated in Figs. 2 and 4 are preferred forms because the same will form a substantially watertight connection around the insulated conductor, in addition to holding the conductor immovable with respect to the contact or terminal, but where the coupling is used where it is not exposed to weather or moisture the twine, cord or rings may be used.

My invention is capable of application to many devices in which that character of an electrical connection as I have above de-

scribed, is desirable. Thus, as above set forth, the device lends itself particularly to the attaching of the secondary wires of a 5 sparking circuit to the contacts or terminals of a contact device such as is used for automatic engines, but I do not wish to be construed as being limited to this application of my invention for other forms and other 10 applications thereof are fully contemplated by me so long as the same are within the spirit and scope of my invention and of the appended claims.

Having thus described my invention what I claim and desire to protect by Letters 15 Patent of the United States is:

1. In a device for uniting insulated conductors of electricity, the combination of a mounting having an opening, a conductor rigidly secured to such mounting and having 20 its end at the bottom of said opening, the said conductor being provided with a recess in the end thereof, a second conductor provided with a short bared end arranged to enter said recess in said first mentioned conductor, a water proof material fitting tightly around the insulated end of said second conductor and having an exterior diameter substantially equal to the interior diameter of 25 said opening, said material being compressed around said conductor and filling said opening when the coupling is secured to said support.

2. In a device for uniting insulated conductors of electricity, the combination of a support, a conductor mounted in said support and provided at its outer end with a recess, said support being provided with an opening having a conical surface around 30 said end of said conductor, a second conductor having a bared end arranged to fit within said recess in said first mentioned conductor, a coupling having an opening through which said second conductor passes, a plurality of convolutions of adhesive tape 35 wrapped around said second conductor adjacent said bared end to form a cylindrical flange of a diameter substantially equal to that of the interior of said opening, a shoulder on said coupling to engage the side of 40 the convolutions of said tape adjacent thereto, said coupling being screw threaded to said support.

3. In a device for uniting a pair of electrical conductors, the combination of an electrical conductor, a substantially cylindrical mounting provided with screw threads and to which said conductor is rigidly secured 45 in axial alinement therewith, said mounting

being provided with a conically recessed clamping surface around the end of said conductor, a second conductor provided with an insulating covering and a relatively short bared end, a cap having an axial opening through which said second conductor extends, and an interior clamping surface in 50 a plane substantially normal to the axis of said opening in said cap, and a plurality of convolutions of a length of flexible material tightly wound around said second conductor adjacent said bared end and forming a 55 flange thereon of a diameter substantially equal to that of the interior of said cap, said cap being provided with screw threads co-operating with the screw threads of said mounting, whereby when said cap is turned 60 with respect to said mounting, to move toward said mounting, the said flange is clamped between the said clamping surfaces of said mounting and said cap, the radial expansion of said flange is substantially prevented by the walls of said cap, the flange is pressed more tightly against said second 65 conductor by reason of the concave surface of said mounting; and said bared end is forced toward and securely held against said 70 first conductor.

4. In a device for uniting a pair of electrical conductors, the combination of a support, an electrical conductor secured to said support, said support being provided with 75 a conical recess surrounding the end of said conductor, a cap having an opening, a second conductor having a bared end, passing through said opening in said cap, a length of flexible material wrapped around said 80 second conductor to form a flange adjacent the bared end thereof and within said cap and of an exterior diameter substantially 85 equal to that of the interior of said cap and means whereby said cap may be forced 90 toward said support, to clamp said flange between said cap and surface of said conical recess in said support, the radial expansion of said flange is substantially prevented by the sides of cap, the said flange is made to 95 grip said second conductor more tightly and the bared end of said second conductor is pressed into and retained in firm engagement with said first conductor.

In witness whereof I have set my hand 100 this twenty-first day of January 1911.

ARTHUR ATWATER KENT.
